UNITED STATES PATENT OFFICE.

BENJAMIN MOSS, OF NEW YORK, N. Y.

MARKING-TOOL.

1,381,131.

Specification of Letters Patent. Patented June 14, 1921.

Application filed July 26, 1920. Serial No. 398,876.

To all whom it may concern:

Be it known that I, BENJAMIN MOSS, a citizen of the United States, residing at New York, in the county and State of New York, have invented certain new and useful Improvements in Marking-Tools, of which the following is a full, clear, and exact specification.

This invention relates to tools for marking material for plaiting or for producing parallel marks for other purposes, and it is the object of the invention to provide a device of this kind which is simple in construction, easy to operate and capable of a wide range of adjustments.

A special object is to improve the construction of the marking points and adapt them for the use of detachable and adjustable tips or markers. Another object is to provide for adjusting the lazy-tongs carrying the marking points at an inclination to the horizontal so as to raise all but one set of marking points out of contact with the surface to be marked. Other objects will appear as the description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:

Figure 1 is a plan view of a marking tool constructed substantially in accordance with this invention.

Fig. 2 is a perspective view of a part of said tool.

Fig. 3 is a detailed view on a larger scale of one of the marking points, partly in section.

Fig. 4 is a plan view of the marker clamp on a still larger scale.

Fig. 5 is a detailed perspective view of one of the members of the cam acting clamping jaws.

Fig. 6 is a side view of the guide member and carriage of the tool, showing the arrangement of the slots in the latter.

Fig. 7 is a side view of the marking tool, showing the inclined adjustment of the lazy-tongs.

Fig. 8 is a section on the line VIII—VIII of Fig. 1.

Fig. 9 is a plan view of a modified form of the marking tool designed for marking concentric curved lines, and

Fig. 10 is a sectional view of the tip clamp of the marking point on a larger scale.

The device consists of a guide rail 1 which may be of any desired length and secured in place by screws 200 passed through ears 2. A carriage 3 is adapted to slide along said rail 1 over which it fits. To said carriage there is adjustably secured a bar preferably of angle form having a vertical portion 4 and a horizontal portion 5. Said portion 5 of the bar has a long slot 6 extending longitudinally thereof with which the lazy-tongs of the marker hereinafter described is connected.

The carriage 3 has pairs of horizontal slots 10 entering from each end thereof, and a central vertical slot 11. Each of said slots 10 and 11 is of rabbet form adapting them to receive the heads of the bolts 9 between said carriage and the guide rail 1. Said bolts extend through slots 7 arranged vertically in the portion 4 of the adjustable bar, and thumb nuts 8 are fitted on the outer ends of said bolts for clamping said bar in adjusted position. It will be noted by reference particularly to Fig. 7 that the end bolts may be arranged in either of the end slots 10 according to the desired adjustment of the bar, it being possible with the arrangement of slots described to adjust said bar at an incline to the horizontal in either direction, as well as adjust it up and down in a horizontal position.

The lazy-tongs comprises two sets of links 12 and 13 slidably connected at one end with the slot 6 by bolts 15 having tightening nuts 16. A spacing washer 14 is placed between the slotted portion 5 of the bar and the end link 13 to support it on the same level with the upper surface of the links 12. At the intersections of the lazy-tongs links they are swiveled together by marking devices comprising marking tip carriers having adjusting knobs 18 and shanks 19 which are screw threaded on their lower portions as at 20, see Fig. 3. Said shanks 105 pass loosely through the upper links 13 but the lower links 12 are threaded to engage said threaded lower portions of the shanks,

so that the tension between said links may be varied by rotating the shanks by means of the knobs 18.

Each of the carriers carries a marking tip 24 of lead, metal or other suitable material, which is adjustably held between clamping fingers 22 of sector form and each having a cam portion 23 fitting in a cap portion 21 adapted to screw on the lower end of the shank 20. When the cap is screwed up on the shank the cam portions 23 of the clamping fingers come in contact with the end of the shank and cause said fingers to firmly grip the tip 24. By loosening said cap the tip may be removed or adjusted to take up wear or for any other purpose desired.

The inclined adjustment of the bar and lazy-tongs shown in Fig. 7 is desirable when only one set of marking points is to be used. When the bar is adjusted horizontally all of the marking points may be utilized to make a series of parallel lines 25, Fig. 1, as the carriage is moved along the guide rail. As shown in Fig. 9, the lazy-tongs may be connected by converging links 17 to a common point in the slot 6 and said lazy-tongs swung about said point as a center for describing concentric arcs 26. In this modification, the distance between the concentric arcs may be varied by extending or contracting the lazy-tongs, the same as in the preferred form the distance between the parallel lines 25 may be varied. It will be noted that the position of the markers 24 as shown in Fig. 7, serves to bring the markers into an angle position or about as a pencil is held in the hand when writing, and that this position serves to permit the markers to be more smoothly drawn over a surface to be marked than if the marking points were set vertically and that the possibilities of scratching or tearing the surface to be marked are eliminated.

As shown best in Figs. 5 and 10, the concave curve 27 on each of the clamping fingers 22 will cause them to move bodily toward the center when pressure is applied to the ends of the cam portions 23 by screwing up on the cap 21, so that the vertical portions 22 of said clamping fingers will grip the tip 24 uniformly throughout the length of said fingers.

Having thus described my invention, what I claim as new and desire to secure by Letters Patent of the United States is:—

1. In a marking tool, the combination with a guide rail, of a carriage mounted to slide on said rail, lazy-tongs carried by said carriage and extensible in a direction transverse to the guide rail, and marking devices on said lazy-tongs.

2. In a marking tool, the combination with a guide rail, of a carriage mounted to slide on said rail, lazy-tongs carried by said carriage and adapted to be adjusted at an inclination thereto, means for retaining said

lazy-tongs in adjusted position, and marking points on said lazy-tongs.

3. In a marking tool, the combination with a guide rail, of a carriage mounted to slide on said rail, a bar adjustable on said carriage, and lazy-tongs carrying marking devices attached to said bar and extensible 70 transversely to the guide rail.

4. In a marking tool, the combination with a guide rail, of a carriage mounted to slide 75 on said rail, a bar, lazy-tongs attached to said bar to move in the plane thereof, marking devices on said lazy-tongs, the latter being extensible transversely to the guide rail, and means for permitting adjustment of said 80 bar into different positions on said carriage.

5. In a marking tool, the combination with a guide rail, of a carriage mounted to slide on said rail, a bar, lazy-tongs attached to said bar, marking devices on said lazy- 85 tongs, and means for permitting adjustment of said bar on the carriage transversely thereof.

6. In a marking tool, the combination with a guide rail, of a carriage mounted to slide 90 on said rail, a bar, lazy-tongs attached to said bar, marking devices on said lazy-tongs, and means for permitting adjustment of said bar angularly on said carriage.

7. In a marking tool, the combination with 95 a lazy-tongs comprising superposed links, of a marking device connecting said links to swivel on one another, said device having a threaded shank, and one of said links having a threaded passage engaging said 100 threaded shank while the other link has a passage loosely engaging said shank.

8. In a marking tool, the combination with a lazy-tongs comprising superposed links, of a marking tip carrier connecting said links 105 to swivel on one another, and a marking tip detachably connected to said carrier independently of the swivel connection of the links.

9. In a marking tool, the combination with 110 a lazy-tongs comprising superposed links, of a marking tip carrier connecting said links to swivel on one another, and a marking tip adjustable on said carrier.

10. In a marking tool, the combination 115 with a lazy-tongs comprising superposed links, of a marking tip carrier connecting said links to swivel on one another, a marking tip connected to the lower end of the carrier, and clamping jaws for holding said 120 tip in different positions.

11. In a marking tool, a marking tip carrier having a threaded shank, a marking tip, clamping jaws for gripping said tip, and a cap adjustable on the end of the 125 threaded shank and adapted to clamp said jaws about said tip.

12. In a marking tool, the combination with a bar, of a lazy-tongs, marking devices on said lazy tongs, and converging links 130

connecting said lazy-tongs with said bar at a common pivotal point for permitting a series of concentric arcs to be described by swinging the lazy-tongs on its pivotal point 5 of connection with the bar.

13. In a marking tool, a marking device having a threaded shank, a marking tip, clamping jaws for gripping said tip, and a cap adjustable on the end of the threaded 10 shank and adapted to clamp said jaws about said tip, said jaws being angular in form

with vertical gripping portions and inclined cam portions, there being curved exterior angles between said portions to coöperate with said cap for moving the jaws inward bodily to uniformly grip the tip throughout the length of the gripping portions of said jaws. 15

In testimony whereof I have signed my name to this specification.

BENJAMIN MOSS.
